UNITED STATES PATENT OFFICE.

GEORGE A. FORMAN AND EDWARD D. FORMAN, OF BROOKLYN, NEW YORK.

DESIGN FOR A CEILING-PLATE, &c.

SPECIFICATION forming part of Design No. 27,117, dated May 25, 1897.

Application filed April 6, 1897. Serial No. 631,024. Term of patent 3½ years.

To all whom it may concern:

Be it known that we, GEORGE A. FORMAN and EDWARD D. FORMAN, citizens of the United States, residing at Brooklyn, in the county of 5 Kings and State of New York, have invented and produced a new and original Design for Ceiling or Crown Plates for Chandeliers and other Gas-Fixtures, of which the following is a specification, reference being had to the accompanying drawings, which form a part thereof, and in which—

Figure 1 is a bottom plan view of our ceiling or crown plate, and Fig. 2 a central transverse section on the line 2 2 of Fig. 1.

The principal feature of our design consists of a rectangular plate A, which is provided centrally with a tubular depending portion B, around the lower open end of which is formed an outwardly-directed flange C, which is rectangular in form and the edges of which are provided with scallops or convolutions, and within which is a circle of beads D. The lower surface of the plate A is also provided with a central rectangular space formed by 25 depending or raised ribs E, within which are wreaths F and streamers G, all of which appear in relief, and around the central rectangular space or at each side thereof are vase-shaped figures H, between which are vines K, 30 the stems of which are connected with the base of the vase-shaped figures, save at the

corners, where they connect with the corners of the central rectangular figure, and between these vines at the corners plant-shaped figures provided with lance-shaped leaves, as 35 shown at II, and the rectangular plate A is also provided on the lower surface and near the edges thereof with a depending rectangular rim L, within which is placed a row of beads M, and outside of the rim L is a flange 40 O, which is concave in cross-section on its lower surface, as shown in Fig. 2, and the said lower surface of the said flange is also provided with ornamental configuration, as shown at P.

Our design is symmetrical in form and also ornamental in appearance, and,

Having fully described the same, we claim and desire to secure by Letters Patent—

A design for a ceiling or crown plate for 50 chandeliers and other gas-fixtures as herein shown and described.

In testimony that we claim the foregoing as our invention we have signed our names, in presence of the subscribing witnesses, this 5th 55 day of April, 1897.

GEORGE A. FORMAN.
EDWARD D. FORMAN.
